CLAIM

The ornamental design for a mounting stand for suspension of a piece of air conditioning equipment at a uniform height above a flat horizontal roof, as shown and described.

DESCRIPTION

FIG. 1 is a top, left end, and front perspective view of a mounting stand for suspension of a piece of air conditioning equipment at a uniform height above a flat horizontal roof, showing my new design;

FIG. 2 is a front elevation view thereof;

FIG. 3 is a left end elevation view thereof, the opposite end being a mirror image of that shown;

FIG. 4 is a rear elevation view thereof;

FIG. 5 is a top plan view thereof;

FIG. 6 is a bottom plan view thereof.

FIG. 1

FIG. 2

FIG. 3

FIG. 5

FIG. 4

FIG. 6
